MINERAL SEPARATORS

Carl E. Batterson, St. Paul, Minn.

Application September 26, 1957, Serial No. 686,518

14 Claims. (Cl. 210—322)

This invention relates to an improvement in mineral separators and deals particularly with an apparatus for removing solid material from liquid or air containing a solid material. More particularly, the separator is particularly useful in determining the character of mineral being removed from a drill hole during a test drilling operation.

Three methods of testing for minerals removed from drill holes are most commonly used. The first is a core drilling arrangement in which the mineral being drilled is forced into the hollow end portion of the drill and is retained therein. After the drilling has progressed a predetermined distance the drill is removed from the hole, the core is removed, and the hollow drill rod is returned to the hole to drill another core of material. The method involves a great deal of time and labor to remove these cores every 8 to 10 feet. The method is also limited to materials such as rock or solid material. The method is useless in materials such as muds, clays or silica. The second method usually involves continually forcing the material being drilled through the hollow drill rod by means of fluid such as water. The material removed from the drill opening is directed into a suitable settling tank in which the water is allowed to drain off so that the mineral may be inspected or tested. This method is more commonly used when drilling in sands, muds or clays but is also used in rock drilling.

A third method is commonly used when a large water supply is not available. Air is used to force the material up and through the hollow drill steel. The air and drill cuttings are directed into a dust collector where it is partially separated.

The present invention differs from the latter procedures by directing the liquid and minerals or air and minerals removed from the drill hole to a mineral separator which almost instantaneously separates the material from the water and deposits it in a transparent container where it may be constantly visibly noted.

When the air drill system is used in conjunction with the mineral separator, the air is introduced from the drilling machine and into a suitable cone shaped tank. The particles of material in the air flow are saturated upon contact with the water contained in the suitable tank. The water in the separator remains in a closed circuit by discharging the outlet into the suitable tank where it is then pumped back into the separator through a coupling attached to the inlet of the separator.

A feature of the present invention resides in the provision of a series of concentric conical baffles between which the liquid containing the mineral is forced. As the liquid changes direction between the various baffles, the mineral is separated from the water and is collected at the lower ends of the baffles. Means is provided for releasing the minerals into a suitable receptacle.

A further feature of the present invention resides in the provision of a separator which is mounted to overlie a receptacle for containing the minerals. In preferred form, this receptacle comprises a transparent tube con-

2

taining a transparent bag into which the minerals are dropped. When the bag is filled it can be removed and maintained for test purposes. The bags may be marked to indicate the minerals which are collected from various elevations in the drill hole, the minerals stratifying within the bag.

A further feature of the present invention resides in the provision of a mineral separator including a series of concentric cones between which liquid containing mineral is forced and in introducing the liquid bearing the mineral into the outermost of the cones in a manner to provide a swirling action which assists in the separating operation. Alternate cones are provided with open lower ends so that the liquid may pass upwardly through the small diameter end of the cone to flow between the next pair of conical baffles. The other cones are provided with openings near the upper extremity thereof through which the water and mineral may flow to pass between the next pair of baffles. These remaining cones are normally closed at their lower ends with a releasable closure plug. By retracting the plugs, all of the cones may be simultaneously opened to permit the mineral to drain into the receptacle.

These and other objects and novel features of the present invention will be more clearly and fully set forth in the following specification and claims.

In the drawings forming a part of the specification:

Figure 1 is a front elevational view of the mineral separator showing the general construction thereof.

Figure 2 is a vertical sectional view through the apparatus showing the arrangement of parts within the separator.

Figure 3 is a horizontal sectional view, the position of the section being indicated by the line 3—3 of Figure 2.

Figure 4 is a horizontal sectional view through the mineral receptacle, the position of the section being indicated by the line 4—4 of Figure 2.

Figure 5 is a sectional detail view of a modified form of construction.

Figure 6 is a diagrammatic view of the flow diagram when the particles are entrained in air.

The mineral separator is indicated in general by the letter A and is shown as enclosed in a generally octagonal housing 10 which is supported by a pair of oppositely disposed tapered legs 11. The lower ends of the tapered legs 11 are connected by a cross brace 12 having a flat upper surface. Laterally extending arms 13 project from the lower ends of the legs 11 on the plane of the cross member 12, these arms 13 together with the cross member 12 forming an H-shaped supporting base. A nipple or sleeve 14 is welded or otherwise secured to the upper surface of each arm 13 near its outer extremity. Legs 15 are slidably supported in the sleeves 14, each leg including a vertical shank 16 which is slideable in the sleeve 14 and a floor engaging flange 17 at the lower end of the shank. Holes are drilled through the arms 13 in alignment with the apertures of the sleeves 14 so that the legs may be slidably supported. Hand operated set screws 19 extend radially through the sleeves 14 to hold the shanks 16 of the legs 15 in an adjusted position. This arrangement is provided due to the fact that the separator must be supported on a substantially horizontal plane to function most effectively.

As is indicated in Figures 2 and 3 of the drawings, a bottom panel 20 forms a bottom closure for the enclosure 10. An outer conical wall 21 is provided with an externally threaded nipple 22 at its lower end and the cone is provided with a cylindrical sleeve like extension 23 at its upper end. An inlet pipe 24 is supported by the enclosure 10 to extend downwardly through the wall of the enclosure 10 and through the sleeve extension 23 of the cone 21 to overlie the inclined surface of the cone. The upper end of the inlet member 24 is externally threaded

as indicated at 25 to accommodate one end of a flexible hose. The lower end of the inlet indicated at 26 is bent at its extremity so as to cause a swirling motion of the liquid entering the separator. As may be seen from Figure 3 of the drawings, the water forced through the bent end 26 of the inlet 24 will cause the water to swirl in a counterclockwise direction as viewed in this figure. The unthreaded portion of the inlet pipe 24 which projects through the housing wall is enclosed in an outwardly projecting housing portion 27.

A second cone 29 is arranged within the outer cone 21 and is in spaced relation thereto. The cone 29 also includes a cylindrical sleeve-like extension 30. The lower end of the cone 29 is cut off to provide a relatively small diameter opening 28. Liquid forced between the cones 21 and 29 may pass downwardly between these cones and upwardly through the opening 28.

A third cone 31 having a cylindrical top extension 32 is supported within the cone 29 and in spaced relation thereto. The cone 31 is provided with a cylindrical nipple 33 at its lower extremity. The nipple 33 is of materially smaller diameter than the opening 30 so as to provide a space between the cones 29 and 31.

Additional concentric cones 35, 36, 37, 39, 40 and 41 are mounted in spaced relation to one another to provide fluid passages therebetween. These cones are provided with cylindrical extensions 42, 43, 44, 45, 46 and 47 respectively at their upper ends. Preferably, the cones as well as the cylindrical extensions terminate on a substantially common plane at their upper extremities.

The manner in which the various cones are supported is perhaps best indicated in Figures 2 and 3 of the drawings. The outer cone 21 is connected at its upper edge to an inturned flange 49 at the top of the enclosure 10. The top of the cylindrical cone extension 23 is connected to the flange 49 about a peripheral bead 50. The various cones within the outermost cone 21 are held in properly spaced relation by angularly shaped spacers 51 which extend between the outermost cone 21 and the next adjacent cone 29 and by narrower spacers 52 extending between the cylindrical extensions of the remaining cones. The spacers 51 and 52 are spot welded or soldered to the cone extensions which they contact so as to form a solid construction.

A central outlet chamber 53 is supported inwardly of the innermost cone extension 47 and includes a tapered bottom portion 54 terminating in an open lower end 55. A vertical pipe or sleeve 56 extends through the center of the chamber bottom 55 and the upper end of this sleeve 56 is supported by a nipple 57 secured to a channel member 59 bridging the top of the outlet chamber 53. The pipe 56 is designed to slidably support a valve rod 60, the purpose of which will be described.

The lower end of the cone 31 has been described as having a nipple 33 attached thereto. Alternate of the cones described are provided with similar nipples. In other words, the cones 36, 39 and 41 are provided with nipples 61, 62, and 63 respectively. The lower ends of these cones and the juncture between the cones and the nipples forms a seat for a corresponding valve plug. Valve plugs 64, 65, 66 and 67 are mounted upon the valve rod 60 and are vertically movable therewith. These valve plugs are shown in elevated position in Figure 2 of the drawings but normally these plugs would be seated against the lower ends of the cones 31, 36, 39 and 41 to perform a bottom closure for these cones. An additional plug 69 is mounted upon the valve rod 60 and this plug is designed to seat against the lower end of the outer cone 21 at its juncture with the nipple 22. This valve 69 is normally elevated above the seat while the remaining valves are properly located so that all of them seat simultaneously. The valve rod 60 is moved vertically by means of a handle 70 at the upper end of the valve rod. The plugs 64, 65, 66 and 67 are resilient, and are of such size that by urging the valve rod downwardly,

these valves will enter the nipples 33, 61, 62 and 63, respectively and still remain closed when the valve 69 is closed.

With reference to Figure 3 of the drawings, the outer surface of each of the cylindrical cone extensions is provided with a nipple 71 braced or otherwise secured thereto to extend radially, each nipple communicating with an opening through the cone extension. An outlet pipe 72 extends through the aligned sleeves 71 and into the outlet chamber 53. The other end of the outlet pipe 71 is connected by an elbow 73 to a small generally hexagonal enclosure 74 on the exterior of the housing 10. The elbow 73 directs the fluid to a funnel 75 within the enclosure 74, the funnel 75 having a hose connection 76 at its lower end. This hose connection may provide a means of connecting the outlet of the separator to the drilling apparatus. In other words, during the operation of the apparatus fluid is bypassed from the drilling apparatus through the separator and then back to the drilling apparatus so as to maintain a closed circuit.

A resilient gasket 77 is provided with an integral sleeve 79 which encircles the nipple 22 at the lower end of the outermost cone 21. This gasket 77 includes an upwardly curved flange 80 at its lower end, the flange 80 presenting a convex undersurface. In actual practice, the gasket 77 is formed by inverting a rubber sink or toilet plunger. The gasket is held in place by a coupling 81 which projects downwardly from the nipple 22 and is threaded thereto.

A generally semi-circular strip 82 is mounted centrally of the cross member 12, this arrangement being best illustrated in Figures 2 and 4 of the drawings. A plastic tube 83 extends from the cross member 12 to the gasket 77 and is properly located at its lower end by the socket forming strip 82. As is indicated in Figure 4 of the drawings, the tube 83 is longitudinally slit throughout its length as indicated by the numeral 84. The tube is normally held from expansion by a pair of circular steel coil springs 85 and 86. The lower of these springs 86 encircles the lower end of the plastic tube 83 while the other spring 85 encircles the tube near its upper end.

The plastic tube 83 is preferably transparent so that the interior may be seen. A bag 87 having a closed lower end 89 fits within the tube 83 and the lower end of the bag rests upon the cross member 12. The bag 87 is somewhat longer than the tube 83 and the upper end of the bag is folded down to overlie the exterior of the tube as indicated at 90. This downfolded end 90 is encircled by the spring 85.

Having described the construction of the apparatus, the operation thereof is substantially as follows: The coupling 25 at the inlet end of the apparatus is connected to the drill rig to receive the various minerals from the drill hole which are entrained in water. The water enters the inlet pipe 24 and is urged under pressure in a direction generally tangent to the cone 29 so as to cause a swirling action of the liquid and water. When this is taking place, the valve rod 60 and the various valves mounted thereupon with the exception of the bottom valve 69 are in lowered or closed position so that the liquid must flow in a tortuous path downwardly within the outermost cone, upwardly within the next adjoining cone 29 and between the cones 29 and 31 until it reaches the level of the series of angularly spaced apertures 91 in the cylindrical extension 32 of the cone 31. Similar angularly spaced apertures 91 are provided in the cylindrical extensions 43, 45 and 47. A second series of angularly spaced apertures 92 extend through all of the cylindrical extensions which have been described. These apertures 92 are merely overflow apertures which permit the liquid to spill from one area to the other in the event of a sudden surge of liquid into the separator due to surging of the drill pump or any other reason. Due to the swirling action of the water entering the outer cone from the inlet, much of the mineral in the liquid will

drain directly into the bag 87, providing a virtually immediate indication of the minerals being encountered.

After passing through the apertures 91 of the cone extension 32, the liquid passes downwardly between the cones 31 and 35 and then upwardly between the cones 35 and 36 to spill through the angularly spaced apertures 91 in the cylindrical extension 43. The liquid then flows downwardly between the cones 36 and 37 and upwardly between the cones 37 and 39 to spill through the apertures 91 in the cylindrical extension 45. The fluid then flows downwardly between the cones 39 and 40 and upwardly between the cones 40 and 41 to pass through the apertures 91 in the cylindrical extension 47. The fluid then flows downwardly between the cones 41 and 54 and up through the open lower end of the outlet chamber 53 which is connected to the outlet tube 72. The fluid then flows through the elbow 73 and the funnel 75 to the outlet coupling 76 which is connected to a return fluid line.

As the fluid swirls between the various cones the heavy particles of mineral tend to separate from the water partly by centrifugal action and partly by the quick changes of direction at the lower ends of the various cones. As a result, the mineral collects over the various valves 64 through 67 where the fluid is required to reverse direction. After a predetermined period of time, the valve rod 60 is lifted by engagement with the handle 70. This permits the mineral collected adjoining each of the valves to drain downwardly into the bag 87. The mineral is flushed downwardly through the various nipples at the lower end of the valve cones by the fluid which overlies this mineral deposit and all of the mineral is permitted to drain by gravity into the bag. Obviously, the bag 87 receives liquid as well as the mineral, but the mineral drains to the bottom of the liquid to form a layer of mineral which is readily visible through the transparent tube 83 and the transparent bag 87.

The separator described has been found extremely effective and particles of minerals have been separated from liquids even where the specific gravity of the mineral is but slightly greater than that of water. Much of the swirling action takes place within the outermost cone and the next adjacent cone but the liquid passing through the various passages 91 continues to swirl to some extent due to the fact that the openings are large enough to permit the liquid to continue movement in a certain direction.

When the bag 87 is filled, the bag and its plastic tube or sleeve 83 are simultaneously removed by tilting the tube sufficiently to permit it to pass beneath the coupling 81. This is possible due to the resilient and flexible nature of the gasket 77. When the tube and bag have been removed, the springs 85 and 86 are removed from the tube allowing this split tube to expand sufficiently to facilitate the removal of the bag. The bag is sealed at the top, properly labeled, and either retained for the purpose of record or directed to additional testing operation.

The various minerals through which the drill is operating are usually readily visible to the naked eye. When the mineral has stratified in layers in the bag, one layer may be extremely black indicating the presence of one mineral while the next adjacent layer may be an entirely different color such as red, yellow, or intermediate colors. If the hole is being drilled to detect the presence of a certain mineral, the tests will determine visibility when this mineral is being drilled if the mineral is distinctive in appearance. When a layer containing this mineral is reached, frequent tests may be made until the lower level of the layer is reached at which time other minerals will be readily visible. As a result, under most conditions of operation a visible indication may be obtained in an extremely short period of time without the necessity of filtering occasional samples of material to separate the mineral from liquid in order to determine the nature of the material being drilled.

The fact that the lower valve 69 is normally open will

naturally permit by far the greatest share of the minerals to drain into the bag or receptacle. Thus, a continuous visible indication is provided of the material being encountered. The various minerals which are collected in certain of the cones above the plugs 64 through 67 will be somewhat of a mixture of the various materials and accordingly with this arrangement it is desirable to empty the valves at very frequent intervals so as to maintain the various stratas intact in the container.

In place of the manually operable valve system described, these valves may be arranged to function automatically. In Figure 5 of the drawings a modified form of construction is illustrated which in many respects is superior to that shown in Figure 2. In order to simplify the description the various cones shown in Figure 5 and connected parts have been given the same identifying numerals as were used in Figure 2. The valve rod and various valves have been given different identifying numerals as they are not similar to the structures previously described.

In Figure 5 of the drawings 95 is substituted for the valve rod 60 previously described. A valve plug 96 is mounted on the rod 95 near the lower end thereof. This plug 96 is normally suspended above the nipple 22 but may be lowered by downward movement of the rod 95 to close the bottom end of the outer cone 21 to cut off the operation during the time the bag is being changed.

Float balls 97, 99, 100 and 101 are slidably supported on the valve rod 95 and may freely slide on the rod. During operation of the separator, the buoyancy of these float balls holds them in sealing relation against the lower ends of the nipples 33, 61, 62 and 63 respectively. Thus the lower ends of alternate cones are normally closed when the apparatus is in operation.

When sufficient mineral is deposited above any of the float balls, the weight of this mineral will cause the float ball to drop sufficiently to permit the mineral to drain downwardly into the next alternate cone. Thus, at relatively frequent intervals all of the various cones are emptied of mineral, performing the same action as though the valves were manually opened at frequent intervals in the previously described construction. The automatic structure has the obvious advantage of maintaining the various minerals at their proper position in the receptacle.

Figure 6 shows the flow diagrams employed when the apparatus is used with mineral particles entrained in air. The air, with the particles entrained, are introduced into a chamber 105 through an inlet line 106. A pump 107 discharges these particles, mixed with water, through the outlet line 109 to the inlet pipe 24 of the separator A. The outlet connection 76 is connected to a return line 110 to the chamber 105. The liquid in the closed system carries the particles to the separator A, and removes them in the manner described.

In accordance with the patent statutes, I have described the principles of construction and operation of my Improvement in Mineral Separators, and while I have endeavored to set forth the best embodiments thereof, I desire to have it understood that changes may be made within the scope of the following claims without departing from the spirit of my invention.

I claim:

1. A mineral separator for separating minerals from fluid in which they are entrained, the separator including an outer frusto-conical wall and a series of concentric frusto-conical walls supported on a substantially vertical axis within the outer wall, said walls being of gradually diminishing size and supported in spaced relation with the small diameter ends thereof lowermost, said outer wall and every second wall of said spaced walls comprising a first series of walls and including valve means normally closing the lower ends of all but the lowermost thereof, the remaining walls forming a second series of walls and having open lower ends, the spaces on either side of the walls of said first series being in communication at the

upper ends of these walls, an inlet communicating with the space between the outermost wall and the next adjoining wall near the upper end thereof and an outlet communicating with the space within the innermost wall, and means adjoining the lower end of the outer wall for receiving minerals and liquid from within said first series of walls when said valves are opened.

2. The structure described in claim 1 and in which said inlet is constructed to direct the fluid and entrained minerals angularly within said outer wall to impart a swirling motion to the liquid contained therein.

3. The structure described in claim 1 and including means connecting said valves for operation in unison.

4. The structure described in claim 1 and including a valve rod connecting all of said valves and projecting from said frusto-conical walls axially thereof by means of which said valves may be simultaneously operated.

5. The construction described in claim 1 and in which at least the second series of walls includes cylindrical top extensions extending above the level of communication between the spaces on opposite sides of the walls of the first series.

6. The structure described in claim 1 and in which the walls include cylindrical extensions at their upper ends, the cylindrical extensions on the walls of said first series having angularly spaced apertures therethrough forming the communication between the spaces on opposite sides of these walls.

7. The construction described in claim 1 and including cylindrical extensions on each of said walls, the walls of said first series having angularly spaced apertures therethrough forming the communication between the spaces on opposite sides of these walls, all of said cylindrical extensions with the exception of that on the outer wall having a second series of angularly spaced apertures therethrough substantially above the level of the first named apertures.

8. The construction described in claim 1 and in which the means for receiving mineral comprises a bag in sealed relation to the lower end of the outer wall.

9. The construction described in claim 8 and in which the bag is constructed of transparent material.

10. The construction described in claim 1 and in which the means for receiving mineral comprises a tubular support and a flexible bag within said support.

11. The structure described in claim 1 and in which the means for receiving minerals includes a transparent longitudinally split tube, a flexible bag forming a lining

within said tube, and means for normally holding said split tube from expansion.

12. A mineral separator for separating minerals from fluid in which they are entrained, the separator including an outer frusto-conical wall and a series of concentric frusto-conical walls supported on a substantially vertical axis within the outer wall, said walls being of gradually diminishing size and supported in spaced relation with the small diameters thereof lowermost, said outer wall

10 and every second wall of said spaced walls comprising a first series of walls, the remaining walls forming a second series of walls and having open lower ends, the spaces on either side of the walls of the first series being in communication at the upper ends of these walls, an inlet communicating with the space between the outermost wall and the next adjoining wall, and an outlet communicating with the space within the innermost wall, and means connected to the lower end of the outer wall for receiving minerals, a valve rod extending vertically

15 through said walls axially thereof and including a valve movable into engagement with the lower end of the outer walls to close this opening, and a series of valves on said rod movable into and out of engagement with the lower end of said alternate walls to close these lower ends, said

20 series of valves being normally closed when said separator is in operation and the first named valve being normally open during operation.

13. The construction described in claim 12 and in which the valves of said series are movable with said valve

25 rod for actuation thereby.

14. The construction described in claim 12 and in which said valves of said series comprise ball floats held in raised position by their buoyancy when said separator

30 is in operation and filled with liquid, the weight of minerals above said ball floats acting to counteract the buoyancy of the balls when sufficient of the mineral is present.

35

12. The construction described in claim 12 and in which the valves of said series are movable with said valve rod for actuation thereby.

13. The construction described in claim 12 and in which the valves of said series comprise ball floats held in raised position by their buoyancy when said separator

30 is in operation and filled with liquid, the weight of minerals above said ball floats acting to counteract the buoyancy of the balls when sufficient of the mineral is present.
